UNITED STATES PATENT OFFICE

JOHN H. SCHUSSLER, OF CHICAGO, ILLINOIS

INKING MECHANISM FOR PRINTING PRESSES

Application filed May 22, 1922. Serial No. 562,626.

My invention relates to ink fountains for printing presses for the Gordon type of press and has particular reference to an inking fountain having means associated therewith whereby the ink from the fountain is positively fed out of said fountain and controlled in proper amount and properly and effectively distributed before being conveyed to the printing forms.

10 Another and further object of my invention is the provision of an ink fountain having feed means associated therewith in such position that the ink is fed onto a stationary plate or apron in the form of a thin film from whence it is carried by the form rollers to the printing surface of the form, the ink being pre-distributed by the ink fountain roller and duck roller in contact therewith.

20 Another and further object of my invention is the provision of an ink fountain for printing presses of the Gordon type having means associated therewith whereby ink is conveyed to and distributed upon an inking disk prior to its being picked up by the form rollers and conveyed to the printing forms.

Another and further object of my invention is the provision of an inking fountain particularly adapted for use with the apparatus of my co-pending application Serial No. 547,225, filed March 27, 1922, particularly with respect to inking small forms or adapted to ink some portions of the form heavier than the others.

35 Another and further object of my invention is the provision of an inking fountain which is simple and efficient in operation and which is easily installed, and which is highly effective in results.

40 These and other objects of my invention will be more fully and better understood by reference to the accompanying sheets of drawings wherein

45 Figure 1 is a plan view of my improved invention and ink distributing means;

Figure 2 is a side elevational view of the upper portion of the press and ink fountain;

50 Figure 3 is a detail side elevational view of the fountain;

Figure 4 is a view showing the ink fountain control device on lines 4—4 of Figure 3;

Figure 5 is a plan view of the stationary apron upon which the deposit of ink from the fountain is made;

Figure 6 is a detail view partially in elevation and partially in section showing means of mounting the duck roller.

Referring now specifically to the drawings and in which like reference characters refer to like parts throughout, a printing press frame 10 is shown having a pair of pivotally mounted rocker arms 11 and 12 secured thereto in the usual manner, the said arms having form roll trucks 13 and 14 mounted on their forward ends within which the form rollers 15, 16, and 17 are mounted in the usual manner. Secured to the frame 10 of the printing press in any approved manner is a pair of arms 18, 18 on the outer end of which the ink fountain 19 is secured, the ink fountain consisting of a blade or bottom member 20 and a pair of end members 21 and 22 usually formed integral with said bottom member 20 and having a space 23 in

said fountain within which ink is carried. A fountain roller 24 is provided, mounted within the members 21 and 22 the roller being turned down to form shafts 25 and 25^a upon each of its outer ends, shafts being mounted

30 in the blocks 21 and 22 by means of removable bearing blocks 26 and 27 held in position by means of lag bolts 28. On the outer end of the shaft 25 is mounted an arm 29 with a cam wheel 30 adjacent thereto with a ratchet wheel 31 fixed to said shaft 25 by means of a rivet 32, a pawl 33 pivotally mounted upon the member 29 by means of a pin 34, the pawl 33 being adapted to engage

35 the ratchet wheel 31 so the fountain roller 24 is rotated by the member 29. A rod 34^a is provided which is secured to the rear end of the rocker arm 11 by means of a pin 35 so that the rod 34^a is given an up and down movement by the operation of the rocker arm 11 as it carries the form roller over the chase and the inking plate. The rod 34^a extends through the outer end of the member

40 39 and has a pair of adjustable collars 36 and 37 thereon, one on each side of the member

45 40 41 42 43 44 45 46 47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100

29. The collar 36 is held in position on the rod 34 by means of a set screw 38 while the collar 37 has a transverse slot 39 extending therethrough with a transversely extending recess 40 extending across the lower face of the member 37 at right angles to the slot 39. Pins 41, 41 are placed through the rod 34^a in spaced relation to each other, so that the movement of the arm 29 is controlled by the position of the collars 36 and 37 upon the rod 34. In the position shown in the drawings the rod 34^a on its upward movement will move the member 29 its maximum amount giving the fountain roller 24 the maximum amount of rotation and carrying the maximum amount of ink out of the fountain on its surface. The collar 37 is moved by turning the same on the rod 34 and slipping the collar 37 downward over the pins 41 and then turned upon the rod 34^a so that one of the pins 41 will rest in the recess 40 in the collar 37 when so positioned upon any of the pins below the position shown in the drawings the rod 34^a slides through the member 29 and is pushed upward only a short distance so that the fountain roller 24 is rotated only a short distance on the downward pull of the rod 34^a.

Extending through and slidably mounted in the members 21 and 22 is a pair of rods 42 and 43 having their lower ends 44 and 45 flattened and having springs 46 and 47 encircling the said rods at their upper portions and abutting against the members 21 and 22 at their lower ends and against end blocks 48 and 49 which are secured to each of the rods 42 and 43 by means of set screws 50, 50 and have a transversely extending rod 51 connecting the said blocks 48 and 49 and which has a centrally mounted downwardly extending link 52 secured thereto with a pull rod 53 extending therethrough with a pair of collars 54 and 55 on the said pull rod on each side of the member so that the movement of the rod 53 is communicated to the rods 42 and 43 through the link 52 and cross-rod 51. Mounted upon the flattened lower ends 44 and 45 of the rods 42 and 43 is a duck roller 56 having a hollow shaft 57 extending therethrough which is mounted upon a pin 57^a extending through the bearing block 58, and upon a spring mounted pin 57^b positioned within a shell 57^c mounted in the bearing block 59, the bearing blocks being secured to the lower ends 44 and 45 of the rods 42 and 43 by means of screws 60, 60 having springs 61 at the upper sides thereof so that the duck roller 56 is resiliently mounted upon the bearing blocks 58 and 59 and is normally held in contact with the fountain roller 24 by the springs 46 and 47. The duck roller 56 is removably mounted by pulling out the spring pressed pin 57^b in the shell 57^c and its tension upon the apron

hereinafter described is controlled by the springs 61, 61.

The bearing blocks 58 and 59 have upwardly projecting portions 62 and 63 extending upward therefrom having U-shaped recesses in their upper ends within which a roller 64 is mounted, the roller 64 being turned down at each of its ends to form shaft portions which ride in the members 62 and 63 and resting by gravity upon the duck roller 56. The bearing portion of the shafts of the duck roller 56 and roller 64 are turned down slightly smaller than the portions extending from the rollers to the bearings so that shoulders are formed thereon to prevent longitudinal movement of the rollers. Upon the lower end of each of the rods 42 and 43 and in threaded engagement therewith are placed nuts 65 and 66 which are so adjusted that the force of impact of the duck roller 56 against the fountain roller 24 thereby controlling the amount of ink picked up by the duck roller 56.

Mounted upon the printing press frame 10 is the usual circular rotatably mounted ink disk 67 having spaced teeth 68, 68 on the lower side thereof adapted to be engaged by a latch 69 pivotally mounted upon a rocker arm 70 by a pin 71, a second rocker arm 72 being provided having and carrying a shaft 73 at its inner end to which the arm 70 is secured and upon which a second arm 74 is positioned, held on the shaft 73 by means of a set screw 75, the rod 53 being connected to the outer end of the arm 74 by means of a clevis 76 through which a pin 77 extends. Mounted in the outer end of the arm 72 is a roller 78 which travels upon a cam 79 secured to the rear side of the rocker arm 11 and which has a rear portion 80 extending to the lower end of the rocker arm 11 and to the side of which is secured a second cam member 81 by means of a bolt 82 and which has the effect when the rocker arm is in a longitudinal position with the form rollers over the chase, of moving the rocker arm 72 upward pulling the rod 53 so that its motion is communicated by means of the rods 42 and 43 to the duck roller 56 pushing it outward and causing it to deposit ink upon an apron 83 having arms 84 and 85 projecting upward therefrom and which is hingedly secured to the members 21 and 22 by fastening means extending through holes 86 in the arms 84 and 85. The apron 83 extends downward over the upper edge of the inking disk 67 and with each movement of the inking rollers over the chase has a supply of ink applied to the upper surface thereof by means of the duck roll 56 which is held in normal position in contact with the fountain roller 24 and secures its deposit of ink from the surface of this roller 24. The upper form roll 15 coming up onto the apron 83, picks up a supply of ink therefrom and carries it downward over the inking disk 67.

from whence portions of it are picked up by the other inking rolls 16 and 17, and over the form with each printing operation of the press.

- 5 Each of the rocker arms 11 and 12 is mounted upon a shaft 87 extending transversely of the frame 10 and eccentrically mounted with respect to the frame 10 with an operating lever common to printing presses of this type connected thereto so that the press bed is held out of contact with the form, this device being common to presses of 10 this type and known as a "throw-off." On the shaft 87, I place a strap 88 with a bolt 89 extending therethrough on the outer end of which is an arm 90 which extends upward and is secured to the eccentric member 30 mounted upon the shaft 25 of the fountain roller 24. A roller 91 is positioned on the 15 side of the pawl 33 in peripheral contact with the cam 30. The roller 91 holds the pawl 33 out of engagement with the ratchet 31 when the press is thrown off, that is, when the shaft is turned so the press bed does not come in 20 contact with the form. Throwing the press "off impression" automatically turns the cam roller 30 so that the cam surface thereof is in contact with the roller 91 thus holding the pawl 33 out of engagement with the ratchet 25 wheel 26 so that as the press continues in operation the fountain roller 24 is stationary and no ink is fed out of the fountain. As soon as the press is thrown into "impression," the cam 30 is rotated by the arm 90 so the roller 25 91 is out of engagement with the surface of the cam 30, allowing the dog 33 to engage in the teeth on the ratchet wheel 26 so that ink is fed from the fountain by the roller 24 and picked up therefrom by the duck roller 56.
- 40 In operation of the device, ink is placed in the fountain 20 and if a full form is used, ink is placed along the entire length of the fountain 20 and as the press starts in operation, the fountain roller 24 is turned in a clockwise direction by the dog 33 in the member 29, the amount of rotation of the said roller 24 being controlled by the position of the collar 37 as heretofore described. The member 29 has a transverse slot 92 extending thereacross through which the pins 34 pass when the collar 37 is positioned upon any of the pins below the upper one so that the amount which the fountain roller 24 is turned is controlled by the position of the collar 37 and if it is desired to carry out of the fountain a large amount of ink the arm 29 is given a full movement, the collar 37 being in the position shown in the drawings. If it is desired to move the roller 24 only a 45 short distance, say one notch of the ratchet wheel, the collar 37 is placed upon the lowermost pin 41 whereupon the rod 34a slides through the member 29 and the member 29 is moved upward only a short distance. The duck roller 56 is in rolling frictional contact
- with the fountain roller 24 at the time it is turned and receives upon its surface a supply of ink from the fountain roller 24, the amount of movement of the fountain roller 24 determining the amount of surface of the 70 duck roller 56 which is supplied with ink, and therefore the quantity of ink delivered by the duck roller onto the apron 83. In the position shown in the drawings, the inking rollers are in contact with the inking plate and as the rollers pass downward over the forms, the cam 81 engages the roller 78 and through the action of the rocker arms 72 and 74, the duck roller 56 is pushed outward so that a deposit of ink is left upon the apron 75 80 85 90 95 100 105 110 115 120 125 130

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. Inking mechanism for printing presses comprising in combination a pair of rocker arms, an inking carriage carried by said rocker arms, an inking plate, an inking fountain adjacent said plate, a feed roller mounted upon said inking fountain, a pair of rods, mounting members for said rods, an inking member carried by said rods adapted to alternately engage the said feed roller and the said ink plate, the roller being adapted to travel over the inking face of the inking plate, a cam, a crank member operated by the said cam, and means adapted to co-act with the said crank member whereby the said inking member is moved from said inking plate against the said feed roller.

2. Inking mechanism for printing presses comprising in combination a pair of rocker arms, an inking carriage carried by said rocker arms, an inking plate, an inking fountain adjacent said plate, a feed roller mounted upon said inking fountain, a pair of movably mounted rods, an inking member carried by said rods adapted to alternately engage the said feed roller and the said ink plate, a cam operated by said rocker arms, a crank member operated by the said cam, connecting means between said rods and said crank, and springs carried by said rods adapted to co-act with the said cam whereby the said inking member is moved from said inking plate against the said feed roller.

3. Inking mechanism for a printing press comprising in combination, a pair of rocker arms, an inking carriage carried by said rocker arms, an inking plate, an ink fountain adjacent said plate, feed means carried by said fountain, a pair of slidably mounted rods, a duck roller mounted upon said rods, a bell crank carried by said press, a cam member carried by one of said rocker arms adapted to actuate said bell crank, and an operating connection between said bell crank and said slidably mounted rods.

4. Inking mechanism for a printing press comprising in combination, a pair of rocker arms, an inking carriage carried by said rocker arms, an inking plate, an ink fountain adjacent said plate, feed means carried by said fountain, a pair of slidably mounted rods, a duck roller mounted upon said rods, a bell crank carried by said press, a cam member carried by one of said rocker arms adapted to actuate said bell crank, an operating connection between said bell crank and said

slidably mounted rods, and a spring carried by said slidably mounted rods adapted to bring said duck roller into contact with the ink feeding roller.

5. In combination with a printing press, an inking plate secured thereto, pivotally mounted rocker arms on each side of said press, an inking carriage on the outer ends of said rocker arms, an inking fountain secured to said printing press, a feed roller rotatably mounted in said ink fountain, connecting means between said roller and the rocker arms for rotating the said feed roller, a pair of slidably mounted rods in said ink fountain, a rotatably mounted duck roller secured to the lower ends of said rods, springs mounted upon said rods for holding the duck roller in normal contact with said feed roller, a bell crank mounted upon the printing press frame, an actuating cam for said bell crank carried by one of said rocker arms, and means connecting said bell crank and said slidably mounted rods.

6. In combination with a printing press, an inking plate secured thereto, pivotally mounted rocker arms on each side of said press, an inking carriage on the outer ends of said rocker arms, an inking fountain secured to said printing press, a feed roller rotatably mounted in said ink fountain, connecting means between said roller and the rocker arms for rotating the said feed roller, a pair of slidably mounted rods in said ink fountain, a rotatably mounted duck roller secured to the lower ends of said rods, springs mounted upon said rods for holding the duck roller in normal contact with said feed roller, a bell crank mounted upon a printing press frame, an eccentric secured to the rear end of said rocker arm, and connections between the bell crank and the rods whereby the duck roller is pushed down onto the inking plate.

7. In combination with a printing press, an inking plate secured thereto, pivotally mounted rocker arms on each side of said press, an inking carriage on the outer ends of said rocker arms, an inking fountain secured to said printing press, a feed roller rotatably mounted in said ink fountain, connecting means between said roller and the rocker arms for rotating the said feed roller, a pair of slidably mounted rods in said ink fountain, a rotatably mounted duck roller secured to the lower ends of said rods, springs mounted upon said rods for holding the duck roller in normal contact with said feed roller, a bell crank mounted upon a printing press frame, a triangularly shaped track member mounted upon the rear end of one of said rocker arms, and connections between the bell crank and the rods whereby the duck roller is pushed down onto the inking plate where-

by a deposit of ink is made upon said inking plate.

8. In combination with a printing press, an inking plate secured thereto, an inking fountain, a rotatably mounted feed roller in said ink fountain, a pivotally mounted apron secured to said ink fountain, and extending down over the said inking plate and means whereby the ink is conveyed from said feed roller onto said apron.

10 9. Inking mechanism for printing presses comprising in combination a pair of rocker arms, a form inking carriage carried by said rocker arms, an inking plate, fountain adjacent said inking plate, an inking roller mounted upon said inking fountain, an auxiliary inking carriage adapted to convey ink from said fountain onto said inking plate, means for movably mounting the said auxiliary inking carriage onto the fountain including a pair of spaced rods upon which said auxiliary inking carriage is mounted, operating connections between said rocker arms and said auxiliary inking carriage, including a cam actuated by said rocker arms, and connections between the said cam and said auxiliary inking carriage whereby the latter is actuated.

20 Signed at Chicago, Illinois, this 17th day
25 of April, 1922.

JOHN H. SCHUSSLER.
